OUTBOARD MOTOR WITH FLUID CLUTCH

Dale D. Kloss, Minneapolis, Minn., assignor to
 Champion Motors Company, New Brighton,
 Minn., a corporation of Minnesota

Application February 9, 1950, Serial No. 143,280

26 Claims. (Cl. 115—17)

1

This invention relates to outboard marine motors and more particularly to improved power transmission mechanisms for such motors.

Among the important objectives of the invention is the provision of an outboard motor providing greatly improved maneuverability of boats equipped therewith and, generally, having greater overall utility than conventional motors.

Another object of the invention is the provision of an improved variable speed drive for outboard marine motors.

A further object of the invention is the provision of an improved power transmission or drive mechanism for outboard motors providing neutral drive and variable speed drive.

A further object of the invention is the provision, in an outboard motor, of an improved variable speed power transmission mechanism of the type wherein variable speed drive is achieved by a slippage clutch. As is well known, the achieving of variable torque transfer or speed drive by means of slippage clutches is accompanied by generation of heat which must be dissipated at a satisfactory rate to prevent overheating and damage to the parts. The instant invention is, therefore, directed toward the provision of an improved drive for outboard motors involving a slippage clutch for the purpose of obtaining variable speed drive, and wherein heat generated by the slippage clutch is dissipated to the water in which the propeller of the motor is submerged, at a sufficient rate to insure cool operation of the mechanism. To this end, the slippage clutch of the power transmission mechanism is contained within a cavity of the normally submerged portion of the housing structure of the motor, and is submerged or largely submerged in fluid contained within said cavity, and through which fluid and housing structure the heat generated by the slippage clutch is rapidly dissipated to the body of water in which the said portion of the housing structure of the motor is normally submerged.

Another still further object of the invention is the provision, in an outboard motor, of an improved variable speed drive involving a fluid coupled torque transfer unit.

Still another object of the invention is the provision, in an outboard motor, of an improved fluid drive including an improved variable slippage fluid clutch.

An important feature of the invention is the provision, in an outboard motor, of a variable speed drive involving a unique combination of variable slippage clutch, friction brake and con-

2

trol means therefor, providing improved control of the variable torque transfer factor of the slippage clutch.

As another important feature of the invention, I provide, in an outboard motor structure, a variable speed drive involving a unique combination of variable slippage clutch and positive-acting clutch means for locking the relatively rotary elements of the slippage clutch against rotation.

As a further feature of the invention, I provide, in an outboard motor structure, a unique combination of variable slippage clutch, positive-acting clutch for locking the friction clutch elements against slippage, a friction brake, and common control mechanism for the slippage clutch, positive-acting clutch, and friction brake.

The above and other highly important objects, advantages and important features of the invention will be made further apparent from the following specification, claims and appended drawings.

In the accompanying drawings, like characters indicate like parts throughout the several views.

25 Referring to the drawings:

Fig. 1 is a view in side elevation, with some parts broken away and some parts shown in section, of an outboard marine motor incorporating a preferred embodiment of the invention;

30 Fig. 2 is a greatly enlarged fragmentary sectional view, with some parts broken away and some parts shown in axial section of the lower normally submerged portion of the motor structure of Fig. 1;

35 Fig. 3 is a perspective view on the scale of Fig. 2 of a propeller shaft shown in section in Fig. 2;

Fig. 4 is a detail perspective view on the scale of Fig. 2 of the front wall portion of a fluid drive unit or clutch shown in section in Fig. 2;

40 Fig. 5 is a detailed fragmentary sectional view on the scale of Fig. 2 and taken on the line 5—5 of Fig. 2;

Fig. 6 is a detailed sectional view on a still further enlarged scale, taken on the line 6—6 of Fig. 2;

45 Fig. 7 is a fragmentary detail sectional view, taken on the line 7—7 of Fig. 6; and

Fig. 8 is a detail sectional view taken on the line 8—8 of Fig. 6.

50 In the drawings, the invention is illustrated in conjunction with an otherwise standard commercial type of outboard marine motor involving the usual power head, indicated as an entirety by 1 in Fig. 1, and which may be assumed to be in the nature of a conventional internal combus-

tion engine involving the usual pull starter knob 2 and combined throttle and spark control lever 3. Depending from the power head 1 is a hollow drive shaft housing structure 4 involving a normally submerged unit or portion 5 that is detachably secured to the lower part of the housing structure 4 by stud screws or bolts 6 or the like. The motor structure illustrated is provided with conventional clamping means 7 (see Fig. 1) for detachably anchoring the outboard motor to the transom of a boat, not shown. The clamping means 7 is anchored to the upper portion of the depending housing structure 4 by means of a suitable bearing collar 8 (see Fig. 1) surrounding the upper cylindrical portion of the housing structure 4 and in which the said portion of the housing structure 4 is vertically journaled for pivotal steering movements of the power head 1 and depending housing structure 4 and 5. For the purpose of imparting pivotal steering movements to the motor in the bearing collar 8, there is provided the customary steering bar or arm 9.

Extending downwardly from the power head through the depending housing structure 4 and into the lower unit 5 thereof is a vertically disposed drive shaft 10 (see Figs. 1 and 2), that is suitably journaled in the upper and intermediate portions of housing structure 4. This drive shaft 10 is driven from the power head and may be assumed to be directly and conventionally coupled to the crank shaft thereof, not shown. The intermediate portion of drive shaft 10 is journaled in a suitable bearing 11 within housing structure 4, and the lower end thereof is journaled within the lower unit 5 of the housing structure, by means of sleeve bearings 12 and 13, all as best shown in Fig. 1.

The motor structure illustrated is provided with a conventional marine propeller 14 that is mounted on the rearwardly projecting end of a propeller shaft 15 and to which the said propeller is connected for common rotation by means of the usual shear pin 16 (see Fig. 2). The propeller shaft 15 is journaled in the lower housing unit 5 by bearing means comprising a ball bearing set 17, and the inner end portion of said shaft 15 is contained within a large cavity 18 within the normally submerged housing unit 5.

As a feature of the invention, I provide, for coupling the lower end of drive shaft 10 to the propeller shaft 15, power transmission mechanism contained within cavity 18, and immediately to be described. In accordance with the preferred embodiment of the invention illustrated, this power transmission mechanism comprises intermeshing bevel gears 19 and 20, and a fluid drive unit or slippage clutch, indicated as an entirety by 21 (see Fig. 2). The bevel gear 19 is mounted fast on the lower end of drive shaft 10, and its companion gear 20 is mounted fast on an elongated rearwardly extended tubular hub 22 of the front wall 23 of the outer shell or casing of the fluid drive unit or slippage clutch 21 (see Fig. 2). Preferably, and as shown, the bevel gear 20 is screw-threaded on the hub 22 and tightly against the front wall 23, as shown at 24 in Fig. 2. The said outer shell or housing structure of the fluid drive unit 21 further comprises a rear end wall 25 axially spaced from the front end wall 23, and an intermediate generally annular peripheral wall 26 to which the end walls 23 and 25 are securely anchored by screws or the like 27 in a manner to provide a fluid-tight cell between the interior of the shell or housing structure 21 and the cavity 18. By reference particularly to

Figs. 2, 7 and 8, it will be seen that the shell or casing structure 21 is journaled in the normally-submerged unit or portion 5 of the housing structure 4, concentrically of the propeller shaft 15, by means of a stationary sleeve bearing 28 having circumferentially-spaced axially-extended oil channels 29 in its inner surface. The sleeve bearing 28 may be assumed to be press-fit into a receiving bore in the lower housing unit 5.

The fluid drive unit or clutch illustrated is structurally closely analogous to certain fluid pumps and further comprises an inner body element or rotor 30 mounted fast on the propeller shaft 15 by means of spline keys 31 on the intermediate portion of propeller shaft 15. This inner body element or rotor 30, which in its broader aspects is closely analogous to conventional pump rotors, is formed with a circumferentially-spaced plurality of radially outwardly opening vane channels 32, one of which is fitted with a sliding vane 33, and the others of which are equipped with similar sliding vanes 34 (see particularly Figs. 2, 5 and 8). For reasons hereinafter clarified, the sliding vane 33 is subject to the outward yielding biasing action of a coil compression spring 35, shown best in Figs. 2 and 5.

In accordance with more or less conventional pump practice, the interior surface of the rotary peripheral wall 26 of the fluid drive unit is made generally elliptical in transverse section to provide therebetween and the circular periphery of the rotor 30 diametrically-opposed generally crescent-shaped chambers 36 and 37, shown best in Figs. 5 and 6. Of course, under normal operating conditions, the sliding vanes 33 and 34 make sealing engagement with the generally elliptical inner surface of the peripheral wall member 28 and move inwardly and outwardly once for each 360° of relative rotation between the rotor-acting inner body element 30 and the rotary outer body element or shell 26. In the preferred embodiment of the invention illustrated, the entire open space within the cavity 18 is filled with a suitable coupling fluid, preferably oil, which serves also as a lubricating medium for the mechanisms within cavity 18, and further as a heat-conducting medium. Also in the preferred embodiment of the invention illustrated, and preferably, the cavity 18 is supplied with oil by gravity action from an annular reservoir-acting cavity 38, also located in the housing unit 5, but above the cavity 18 (see Figs. 1 and 2). The reservoir-acting cavity 38 is concentric with the drive shaft 10 and communicates with the cavity 18 by one or more fluid passages 39, shown best in Fig. 2.

The inner end of the propeller shaft 15 extends into the elongated hub 22 and is journaled therein through the medium of a sleeve bearing 39', shown best in Figs. 2, 7 and 8, and the projected end portion of hub 22 extends into and is directly journaled in a bore 40 in a water pump housing body 41 (see Fig. 2). This water pump housing body 41 closes the front end of the cavity 18. The water pump housing 41, along with mechanism contained within the cavity 18, is removable through the forwardly opening housing bore 42, but is normally held in place by a laterally displaceable section 43 of the lower housing unit 5 (see Fig. 2). By further reference to Fig. 2, it will be seen that the laterally-displaceable section 43 has interlocking tongue and groove connection with the housing unit 5 at 44, and that said displaceable section 43 is normally locked against lateral displacement by means of a spring-pressed locking pin 45, which is acces-

sible for forced retraction through a small bore 46.

The water pump is of the centrifugal impeller type and the housing 41 thereof defines the forwardly opening cylindrical pump cavity 47, the open front end of which is normally closed by a cover plate 48 cut away or otherwise formed to provide at its bottom portion a water intake port 49 and at its upper portion a water outlet port 50 (see Fig. 2). The intake port 49 to the pump chamber 47 receives water from the body of water in which the propeller and lower housing structure are submerged through forwardly opening water intake passages 51 (see Fig. 2). The water discharge or outlet port 50 receives water under pressure from the pump chamber 47 and delivers the same to an upwardly opening passage 52 in the lower housing unit 5, which is in communication with and delivers to a water delivery pipe 53 extending upwardly through the housing structure 4, and which may be assumed to have its upper delivery end connected to the water jacketed space, not shown, of the internal combustion engine power head. For the purpose hereof, it may be assumed that the water jacketed space or spaces of the engine and the exhaust gases of the engine are exhausted downwardly through the interior of housing section 4 and into the water through a discharge spout portion 54 thereof (see Fig. 1). The water pump further comprises, in addition to the housing 41 and other parts described, a conventional vane rotor 55 mounted fast on a tubular pump shaft 56 (see Fig. 2). The tubular pump shaft 56 is journaled at its front end in the cover plate 48 and has its rearwardly-protected end in telescopic spline keyed engagement with forwardly projected end portion of hub 22 journaled within the pump housing 41 (see Fig. 2). In this manner, the tubular pump shaft 56 is driven in common with the hub 22 and the entire housing structure of the fluid drive unit and beveled gear 20, and is amply supported at both ends. It is important to note, by reference particularly to Fig. 2, that a fluid pressure seal 57 is provided between pump shaft 56 and the bore 40 of the pump housing 41, and that an O-ring fluid pressure seal 58 is provided in the annular space between pump shaft 56 and hub 22, whereby the interior of the water pump chamber 47 is isolated from the cavity 18. Further, it is important to note, particularly by reference to Fig. 2, that the rear end of the cavity 18 is pressure-sealed by means of an annular packing 59 surrounding shaft 15 and located rearwardly of the bearing 17, being, in fact, contained within a removable bearing retainer 60.

It should here be noted that the propeller shaft 15 has an elongated forwardly opening bore 61, which aligns with the bore of the tubular pump shaft 56 (see Figs. 2, 3, 7 and 8). Further, it should be noted, by reference particularly to Fig. 2, that the forwardly projecting end of the bore 61, and the inner or front end of the tubular propeller shaft 15 is spaced from the rear end of the tubular water pump shaft 56 to provide therebetween a space 62 which communicates with the space externally of hub 22 through a fluid discharge port 63.

Before further describing the fluid circuit to and from the chambers 36 and 37 of the fluid drive unit or clutch, attention is directed to the following described important features of the invention, and which are, namely, a positive-acting clutch 64 for positively locking the relatively 75

rotary bodies or elements of the fluid drive unit against rotation, and a friction brake 65 (see Fig. 2) for cooperation with the fluid driven unit under conditions of low torque transfer or high slippage to effectively increase the slippage or decrease the actual rate of torque transfer between the power head 4 and propeller 14.

The positive-acting mechanical clutch 64 comprises releasably interlockable driving and driven clutch elements respectively indicated by 66 and 67 (see Fig. 2). The said driving clutch elements 66 are in the nature of circumferentially-spaced clutch dogs formed directly on the rear wall 25 of the fluid driven unit 21 (see Figs. 2, 7 and 8). The cooperating driven clutch elements 67 are in the nature of similar circumferentially-spaced clutch dogs or teeth formed on the opposing face of an axially shiftable head 68 (see Fig. 2) and adapted to be brought into releasable intermeshing driving engagement with the cooperating driving clutch elements 66. The head 68 is annular and is axially slidably mounted on the propeller shaft 15 with which it has spline key driving engagement, as indicated at 69, and as shown best in Figs. 2 and 3. At this point, and also by reference particularly to Figs. 2 and 3, it will be noted that the propeller shaft 15 is provided between the spline keys 69 thereof with an axially elongated slot 70 extending diametrically therethrough, and that the sliding clutch head 68 carries a pin 71, which extends through and works in this slot 70.

The friction brake 65 comprises the shaft-coupled axially shiftable rotary head 68 which serves also as the driven rotary element of the brake, and a non-rotary friction brake disc 72 (see Fig. 2). The friction brake disc 72 is axially slidably mounted on the reduced diameter hub portion 73 of the head 68 and has an annular radially disposed face for frictional engagement with a similar opposed face on the head 68 (see Fig. 2). The friction brake disc 72 is anchored against rotation with respect to the housing structure and is yieldingly biased in the direction of the head 68 by means of a tortuous generally annular spring ring 74 anchored to the housing structure at 75 and to the head 68 at 76 (see Fig. 2).

By reference now particularly to Figs. 2, 7 and 8, it will be noted that the end wall 25 of the fluid drive unit or fluid drive slippage clutch 21 is journaled on the propeller shaft 15 through the medium of a sleeve bearing 76, and that the rotor 30 is provided with an enlarged bore portion adjacent its rear, which provides within the rotor and about the shaft 15 an annular chamber or space 77, which is pressure-sealed by an O-ring seal or packing 78, shown best in Figs. 7 and 8. Further important to note in connection with the structure illustrated is coil compression spring 79, shown best in Fig. 2, and which has one end seating and reacting against the closed rear end of the axial bore 61 of propeller shaft 15, and its other end seated and reacting against the pin 71 carried by head 68; this spring 79 serving to yieldingly urge the head 68 toward a position of interlocking engagement with the rotary outer shell or housing of fluid drive unit 21 and in which position of the head 68 the friction brake is fully released.

Next to be described briefly will be the fluid circuit into, through, and out of the crescent-shaped chambers 36 and 37 of the variable slippage fluid drive unit 21. In this connection it will be noted first that the hollow tubular portion

of the propeller shaft 15 is provided with a circumferentially-spaced series of radial fluid inlet ports 80 (see particularly Figs. 2, 3, and 7) leading outwardly from its axial bore through mating ports in the sleeve bearing 76', which is fast on and rotates with the propeller shaft 15. Next it should be noted that the propeller shaft 15 is provided in axially spaced relationship to the series of ports 80 with a similar circumferentially-spaced series of radial ports 81 (see particularly Figs. 2, 3, 7 and 8) leading from the axial bore thereof to the annular chamber or space 77 surrounding the propeller shaft 15 and defined in part by the rotor 30 (see particularly Figs. 7 and 8). The radial propeller shaft ports 80 communicate with a radially inwardly opening circular channel 82 in the rear end wall 25 of the fluid drive unit 21, as shown clearly in Figs. 2, 7 and 8, which is connected to the diametrically-opposed crescent-shaped chambers 36 and 37 by diametrically-opposed fluid intake passages 83 located in the rear end wall 25 and shown best in Figs. 2, 5, 6, and 7. Coupling fluid is drawn through these passage 83 into the spaces of the crescent-shaped chambers 36 and 37 between circumferentially adjacent vanes 34 or 33 and 34 under relative rotation of the outer shell of the fluid drive unit and the rotor 30 thereof, and is subject to compression between said adjacent vanes 34 or 33 and 34. When conditions are such as to allow circulation of the fluid through the unit, fluid is discharged under pressure from the crescent-shaped chambers 36 and 37 as follows: The fluid compressed within the crescent-shaped chambers 36 and 37 passes through channels 84 and 85 (see Figs. 6 and 8) in the front end wall 23 of the fluid drive unit and flows generally radially inwardly into circumferentially-extended channels 86 (see Figs. 6, 7 and 8) in the front face of the rotor 30 from which the fluid flows into the spaces beneath the vanes 33, and 34, from which spaces the fluid is discharged radially inwardly through a circumferentially-spaced series of rotor ports 87 (see Figs. 7 and 8), each leading from a different one of the several vane-receiving channels 82 of the rotor into the annular chamber 77 (see Figs. 7 and 8); and from thence into the interior bore of propeller shaft 15 through the circumferentially-spaced series of propeller shaft ports 81 (see Figs. 7 and 8), when the valve mechanism, later to be described, is in a condition to allow such discharge of fluid from the interior of the fluid drive unit. For the purpose of manually controlling the flow through propeller shaft intake and outlet ports 80 and 81, respectively, I provide a valve plunger or piston 88 axially slidably mounted in the bore of the propeller shaft 15 (see Figs. 1, 2, 5, 6, 7 and 8). When this valve 88 is in the position shown in the drawings (see Figs. 2 and 7), fluid is allowed to freely enter the pump-like fluid drive unit through then uncovered propeller shaft ports 80 (see Figs. 2 and 7) and connected passages, but is not permitted to be discharged from the fluid drive unit, since the propeller shaft outlet passages 81 (see Figs. 2, 7 and 8) are now closed. In this position of the valve mechanism, the torque transfer factor of the fluid drive unit is at maximum for any given speed. It will be noted that the spaces within the bore of propeller shaft 15 adjacent opposite ends of the valve 88 are connected by ports 89 through said valve 88 (see Fig. 7), so that fluid discharged into the bore of the propeller shaft 15 adjacent the front end of valve 88 may

pass through the valve into that part of the bore at the rear of the valve 88, which is in communication with the coupling fluid within the cavity 18 through the elongated crank shaft slot 70. In accordance with the invention, I preferably provide a common control mechanism for the valve 88, positive-acting clutch 64 and friction brake 65. In accordance with the instant illustration, this is accomplished as follows: The valve 88 is integrally formed on the intermediate portion of a push rod 90 (see Figs. 2, 7 and 8) having its rear end abutted against the pin 71 (see Fig. 2) and formed in axially spaced relation to the valve 88 with a guide head 91 (see Figs. 2, 7 and 8). This push rod 90 projects forwardly through and beyond the front end of the propeller shaft 15 and into the tubular pump shaft 56 (see Fig. 2), where it comes into abutting engagement with one end of a short push rod 92 that works axially slidably within the tubular pump shaft 56 and projects forwardly thereof. This short push rod 92 is provided with a packing channel 93 in which is seated an O-ring packing 94 (see Fig. 2), which effectively seals off the coupling fluid-containing cavity 18. The projected front end of the short push rod 92 engages the lower arm of a bell crank 95 (see Figs. 1 and 2), that is pivoted at 96 to the displaceable element 43 of the housing structure, and works within a cavity 97 in the latter. The upper arm of this bell crank 95 is engaged by the lower end of a long push rod 98 (see Figs. 1 and 2) extending downwardly through and suitably guided in the depending housing structure 4 and 5. The upper end of this long push rod 98 extends upwardly through the upper portion of the housing section 4, as shown best at 99 in Fig. 1, where it is connected to a pivoted manually-operated control lever 100. Without going into detail, it will be clear that the push rod 90 is subject to upward and downward movements responsive to arcuate movements of the arcuate control lever 100, and that with the cooperation of compression spring 79, and bell crank 95, the parts 92, 90, 88, 68 and 72 will partake of corresponding horizontal movements.

Operation

By reference to the drawings, it will be seen that with the parts positioned as illustrated therein, the following conditions prevail, to wit:

(A) The fluid drive unit or slippage clutch is in a condition of maximum torque transfer or minimum slippage due to the fact that valve ports 80 are open to freely admit fluid to the interior of the unit while the fluid discharge ports 81 are closed against discharge of fluid from the fluid drive unit or slippage clutch. It will be understood that even with the parts positioned as shown, the percentage of slippage of the fluid drive unit will be greatest at the beginning of motion and will automatically decrease as the speed of motion increases.

(B) The positive-acting clutch 64 is in a completely released position so as to allow the relatively rotary elements of the fluid drive unit or slippage clutch to partake of whatever small degree of slippage may be inherent in the unit, even with the valve element 88 positioned as shown; and

(C) With the parts positioned as shown, the shiftable head 68 is in an intermediate position, wherein the friction brake 65 is just beginning to be applied.

Now, when it is desired to shift the parts so that the power head will idle independently of the

propeller, the control lever 100 is moved from its intermediate position, shown in Fig. 1, to an extreme right-hand position with respect to Fig. 1; this pivotal movement of the control lever causing the following functions, to wit:

The control rod 98 will be shifted downwardly imparting counterclockwise arcuate movement to bell crank 95, causing a corresponding right-hand shifting movement to short push rod 92 and long push rod 90, valve head 88, pin 71, head 68 and brake disc 72, all against the yielding action of compression springs 79, thereby closing fluid intake ports 80 and opening fluid outlet ports 81 of fluid drive unit 21 and applying maximum frictional braking pressure to the friction brake 65. It will be understood that with the parts positioned as just described, the fluid drive unit or slippage clutch 21 will be free to exhaust its internal coupling fluid, while being shut off from the supply of fluid. Of course, under these conditions, it will be impossible to build up a fluid driving pressure between the vanes within crescent-shaped chambers or spaces 36 and 37, or, in fact, at any place within the fluid drive unit or slippage clutch 21, including the spaces within the vane channels 32 beneath the vanes 33 and 34. Hence, the fluid drive unit or slippage clutch will now be in a condition of maximum slippage drive or, conversely stated, in a condition of minimum torque transfer. However, in spite of this, there will be a slight frictional drag within the fluid drive unit 21 tending to impart a slight driving movement to the propeller 14, but this tendency, which may be referred to as the inherent creep of the fluid clutch, will be overcome by the now set friction brake mechanism 65, which will hold the propeller stationary. With the parts positioned as last stated, cranking of the engine will be relatively very easy, since the propeller is idle and will, in itself, produce no resistance to cranking action. Now if the engine be started with the parts positioned as last indicated, or in their extreme right-hand positions with respect to Figs. 1, 2, 7 and 8, the power head or engine 1, drive shaft 10, bevel gears 19 and 20 and the complete outer shell of the fluid drive unit, including walls 23, 25 and 26, will run together but idle free of the vane-equipped rotor 30, propeller shaft 15 and propeller 14. With the power head or engine thus idling or running free, the torque transfer of the fluid clutch may be gradually increased from minimum by gradually moving the control lever 100 in a counterclockwise direction from its extreme right-hand position, last described, back toward its intermediate position shown, and which movement produces a corresponding right to left-hand movement of the valve head 88, shiftable head 68 and clutch disc 72 toward the intermediate position of the drawings. This movement may be gradual or by steps and will result in a gradual, progressive, release of the friction brake 65 and a gradual opening of intake ports 80 and a gradual closing of fluid outlet ports 81 to the point where the ports 81 are fully closed and the ports 80 are fully open and the friction brake is fully released. During the time that the valve 88 is positioned so that the ports 80 and 81 are both partially open, the fluid drive unit will function much as a pump causing a continuous circulation of coupling fluid therethrough under the action of the rotating vanes, and driving force or torque transmitted to the propeller will vary with various intermediate adjustments of the valve 88

resulting in varying restriction to fluid flow through the fluid clutch.

With the unit described, the efficiency of the fluid clutch and the resultant torque transfer factor thereof will increase from the beginning of motion with the increase of speed, due to centrifugal action on the vanes 33 and 34, causing the latter to come into tighter sealing engagement with the arcuate inner surfaces of the outer wall 26. However, it is important to note, in connection with the present device, that this centrifugal action to increase the sealing characteristics of the rotor vanes 33 and 34, does not come into operation immediately upon starting of the engine, since initially power is applied by the power head only to the outer shell of the fluid clutch. Hence, at complete idle and at slow operating speeds, when the rotor 30 is traveling much slower than the power-head driven outer shell of the unit 21, leakage past vanes 33 and 34 will be relatively great due to lack of centrifugal sealing action on the vanes, and the power transfer factor of the unit will be comparatively very low as compared to what it would be with the vane-equipped rotor 30 positively driven from the power head and at a definite speed with respect thereto. In fact, it is because of this action that it is highly desirable to outwardly bias the vane 33 by the spring 35 in order to insure sufficient seal and consequent fluid pressure internally of the unit to insure starting of the rotor. As the pressure within the unit builds up, the vanes 33 and 34 will be forced into tighter and tighter sealing contact with the inner surface of the wall 26 and the combined action of centrifugal force and by increasing fluid pressure beneath the vanes 33 and 34.

Preferably and with the structure illustrated, the friction brake 65 is gradually applied and released coincidentally with the opening and closing of the ports 80 and 81, but in some cases, it has been found desirable to slightly alter the structure so that under left to right-hand movements of the valve 88, the ports 80 will be completely closed to place the fluid clutch in a condition having minimum torque transfer factor before beginning to apply the friction brake 65. Of course, this revision may be accomplished by the simple expedient of positioning the valve head slightly to the right with respect to Fig. 2, sufficiently to cover ports 80, but without changing the axial positions of the other axially shiftable ports. When this is done, unidirectional movements of the control arm or lever 100 will progressively place the valve 88 in a position of maximum fluid clutch slippage or minimum torque transfer, and then progressively apply the friction brake 65.

With the arrangement illustrated, the fluid clutch is utilized for idling of the power head or engine and for permitting variable speed of the power head with respect to the propeller for slow speed operation, such as trolling, so as to permit the engine to operate at all times at an efficient speed and well above its stalling speed, even though the propeller may be operated at a very low speed.

However, once the engine or power head has reached efficient operating speed, which may be assumed to be about fifty percent of its maximum speed, the fluid clutch will automatically assume a condition of very low slippage or very high torque transfer, so much so that it is then serving no particularly useful function which

cannot more effectively be accomplished by a positive drive. Hence, under these conditions, it becomes desirable to achieve a positive non-slippage drive. With the arrangement illustrated, this is achieved automatically upon progressively moving the control lever 100 in a left-hand direction with respect to Fig. 1, to increase the engine speed beyond its mid-range; this action causing a left-hand shifting of the head 68 to an extreme left-hand position, not shown, but causing positive engagement of the cooperating elements 66 and 67 of the positive-acting clutch 64 and consequent locking of the relatively rotary elements of the fluid slippage clutch against further relative rotation.

It will be understood that fluid coupling units or slippage clutches, generally, essentially generate heat under conditions of torque transfer, and thereby presents a cooling problem. It will be seen that in the arrangement illustrated, the heat generated in the fluid coupling unit or clutch 21 will be transferred to the coupling fluid surrounding the said unit and will be passed from thence through the surrounding housing structure to the water in which the propeller is submerged. Otherwise stated, the same coupling fluid, being oil, is utilized for three purposes, namely:

- (1) As a coupling fluid;
- (2) As a heat transfer medium; and
- (3) As a lubricant for the mechanical elements of the structure.

What I claim is:

1. In an outboard motor, a power head, housing structure depending from the power head and including a normally submerged portion defining a cavity, a fluid coupling unit contained within said cavity, said cavity providing a fluid reservoir space adjacent the fluid coupling unit, said fluid coupling unit comprising relatively rotary members and a fluid space therebetween that is in communication with the reservoir space adjacent the coupling unit, power transmission means between one of the said relatively rotary members of the fluid coupling unit and the power head, a propeller shaft journalled in the normally submerged portion of the housing structure with its inner end portion extending into said cavity and coupled to the other of said relatively rotary members of the fluid coupling unit, and a coupling fluid within the fluid reservoir portion of said cavity, whereby heat generated in the fluid coupling unit will be rapidly dissipated to the water in which the housing structure is submerged through the said coupling fluid and housing structure.

2. In an outboard marine motor, a power head, housing structure depending from the power head and including a normally submerged portion, the normally submerged portion of the housing structure defining a fluid reservoir and a transmission mechanism chamber, a fluid coupling unit contained within said chamber; said unit comprising relatively rotary inner and outer fluid coupled body members, the last said member providing a casing for the first said member and a coupling fluid and the interior thereof being in fluid exchange relationship with the submerged fluid reservoir; coupling fluid within the outer fluid coupled member and said reservoir, a driving connection between the power head and one of said fluid coupled body members, a propeller shaft journalled in the submerged portion of said housing structure with its inner end coupled to the other fluid coupled member,

and a propeller mounted on the outer end of said propeller shaft, heat generated in the fluid coupling unit being carried by the driving fluid to the submerged fluid reservoir of the housing structure and being radiated through the latter directly to the water in which the reservoir portion of the housing structure is submerged.

3. In an outboard motor, a power head, housing structure depending from the power head and including a normally submerged portion, a fluid coupling unit contained within the lower part of the normally submerged portion of the housing structure, the said submerged portion of the housing structure defining communicating fluid reservoir spaces immediately adjacent the opposite sides of said fluid coupling unit, said fluid coupling unit comprising relatively rotary members and a coupling fluid space therebetween that is in communication with the said reservoir spaces, a coupling fluid in the space between the relatively rotary members of the fluid coupling unit and within the reservoir spaces adjacent said unit, power transmission means between one of said relatively rotary members of the coupling unit and the power head, a propeller shaft journalled in the lower part of the normally submerged portion of the housing structure with its inner end coupled to the other of the relatively rotary members of the coupling unit, and a propeller mounted on the propeller shaft externally of the housing structure, whereby heat generated in the fluid coupling unit will be rapidly dissipated to the water in which the housing structure is submerged through said fluid and housing structure.

4. The structure defined in claim 3 in which the normally submerged portion of the housing structure also defines a relatively large coupling fluid reservoir chamber above and in communication with the reservoir spaces immediately adjacent the coupling unit, and which serves to further facilitate the rapid transfer of heat from the coupling unit to the water in which the housing structure is submerged.

5. The structure defined in claim 3 in which the normally submerged portion of the housing structure also defines a relatively large coupling fluid reservoir chamber above and in communication with the reservoir spaces immediately adjacent the coupling unit, and which serves to further facilitate the rapid transfer of heat from the coupling unit to the water in which the housing structure is submerged, the last said fluid reservoir extending upwardly substantially to the plane of the top of a circle described by the outer peripheral portion of the propeller.

6. In an outboard motor, a power head, housing structure depending from the power head and including a normally submerged portion, a propeller shaft journalled in and projecting through a wall of the normally submerged portion of the housing structure, a propeller mounted on the outer end of the propeller shaft, driving connections extending through the housing structure from the power head to the propeller shaft and comprising a variable torque transfer slippage clutch, a friction brake within the housing structure between the clutch and propeller shaft, said friction brake comprising a rotary friction element driven by the variable torque transfer slippage clutch and a cooperating non-rotary friction element, and control mechanism for said variable slippage clutch and said friction brake, said control mechanism comprising a common manually shiftable control element to

which said mechanism is responsive to coincidentally and progressively reduce the torque transfer factor of the slippage clutch and apply the friction brake.

7. In an outboard motor, a power head, housing structure depending from the power head and including a normally submerged portion, a propeller shaft journalled in and projecting through a wall of the normally submerged portion of the housing structure, a propeller mounted on the outer end of the propeller shaft, driving connections extending through the housing structure from the power head to the propeller shaft and comprising a variable torque transfer slippage clutch, a friction brake within the housing structure between the clutch and propeller shaft, said friction brake comprising a rotary friction element driven by the variable torque transfer slippage clutch and a cooperating non-rotary friction element, and control mechanism for said variable slippage clutch and said friction brake, said control mechanism comprising a common manually shiftable control element to unidirectional movements of which said mechanism is responsive to progressively reduce the torque transfer factor of the slippage clutch and progressively apply the friction brake.

8. In an outboard motor, a power head, housing structure depending from the power head and including a normally submerged portion, a propeller shaft journalled in and projecting through a wall of the normally submerged portion of the housing structure, a propeller mounted on the outer end of the propeller shaft, driving connections extending through the housing structure from the power head to the propeller shaft and comprising a variable slippage fluid clutch mechanism, said fluid clutch mechanism involving a shiftable element for regulating the torque transfer factor of the fluid clutch, a friction brake within the housing structure between the clutch and propeller shaft, said friction brake comprising a rotary friction element driven by the fluid clutch and a cooperating non-rotary friction element, and control mechanism for the shiftable regulating element of the fluid clutch and the friction brake, said control mechanism comprising a common manually shiftable control element to which said mechanism is responsive to coincidentally and progressively reduce the torque transfer factor of the fluid clutch and apply the friction brake.

9. In an outboard motor, a power head, housing structure depending from the power head and including a normally submerged portion, a propeller shaft journalled in and projecting through a wall of the normally submerged portion of the housing structure, a propeller mounted on the outer end of the propeller shaft, driving connections extending through the housing structure from the power head to the propeller shaft and comprising a variable slippage fluid clutch mechanism, said fluid clutch mechanism comprising a shiftable valve element for regulating the torque transfer factor of the fluid clutch, a friction brake within the housing structure between the clutch and propeller shaft, said friction brake comprising a rotary friction element driven by the fluid clutch mechanism, and a cooperating non-rotary friction element, and control mechanism for said shiftable valve element and the friction brake, said control mechanism comprising a common manually shiftable control element to which said mechanism is responsive to coincidentally and progressive move the shiftable

valve element toward a position of minimum torque transfer and to apply the friction brake.

10. In an outboard motor, a power head, housing structure depending from the power head and including a normally submerged portion, a propeller shaft journalled in and projecting through a wall of the normally submerged portion of the housing structure, a propeller mounted on the outer end of the propeller shaft, driving connections extending through the housing structure from the power head to the propeller shaft and comprising a variable slippage fluid clutch mechanism, said fluid clutch mechanism comprising a shiftable valve element for regulating the torque transfer factor of the fluid clutch, a friction brake within the housing structure between the clutch and propeller shaft, said friction brake comprising a rotary friction element driven by the fluid clutch mechanism, and a cooperating non-rotary friction element, and control mechanism for said shiftable valve element and the friction brake, said control mechanism comprising a single manually operable control element to unidirectional movements of which said mechanism is responsive to progressively move the shiftable valve element toward a position of minimum torque transfer and to progressively apply the friction brake.

11. In an outboard motor, a power head, housing structure depending from the power head and including a normally submerged portion, a propeller shaft journalled in and projecting through a wall of the normally submerged portion of the housing structure, a propeller mounted on the outer end of the propeller shaft, driving connections extending through the housing structure from the power head to the propeller shaft; said driving connections comprising a variable torque transfer slippage clutch, and a releasable positive acting clutch for positively locking the variable torque transfer slippage clutch against slippage; a friction brake within the housing structure between the positive acting clutch and propeller shaft, said friction brake comprising a rotary friction element driven by the variable torque transfer slippage clutch and a cooperating non-rotary friction element, and control mechanism for the variable torque transfer slippage clutch, positive-acting clutch means and friction brake, said control mechanism comprising a common manually shiftable control element to which said mechanism is responsive to first release the positive-acting clutch and then coincidentally and progressively reduce the torque transfer factor of the slippage clutch and apply the friction brake.

12. In an outboard motor, a power head, housing structure depending from the power head and including a normally submerged portion, a propeller shaft journalled in and projecting through a wall of the normally submerged portion of the housing structure, a propeller mounted on the outer end of the propeller shaft, driving connections extending through the housing structure from the power head to the propeller shaft; said driving connections comprising a variable torque transfer slippage clutch, and a releasable positive acting clutch for positively locking the variable torque transfer slippage clutch against slippage; a friction brake within the housing structure between the positive acting clutch and propeller shaft, said friction brake comprising a rotary friction element driven by the variable torque transfer slippage clutch and a cooperating non-rotary friction

element, and control mechanism for the variable torque transfer slippage clutch, positive-acting clutch means and friction brake, said control mechanism comprising a common manually shiftable control element to progressive unidirectional movements of which said mechanism is responsive to first release the positive acting clutch and then progressively reduce the torque transfer factor of the slippage clutch and progressively apply the friction brake.

13. In an outboard motor, a power head, housing structure depending from the power head and including a normally submerged portion, a propeller shaft journalled in and projecting through a wall of the normally submerged portion of the housing structure, a propeller mounted on the outer end of the propeller shaft, driving connections extending through the housing structure from the power head to the propeller shaft and comprising a variable slippage fluid clutch mechanism, said fluid clutch mechanism involving a shiftable element for regulating the torque transfer factor of the fluid clutch, a releasable positive-acting clutch for releasably locking the fluid clutch against slippage, a friction brake within the housing structure between the clutch and propeller shaft, said friction brake comprising a rotary friction element driven by the fluid clutch and a cooperating non-rotary friction element, and control mechanism for the shiftable regulating element of the fluid clutch and friction brake and positive-acting clutch, said control mechanism comprising a common manually shiftable control element to which said mechanism is responsive to first release the positive-acting clutch and then coincidentally and progressively reduce the torque transfer factor of the fluid clutch and apply the friction brake.

14. In an outboard motor, a power head, housing structure depending from the power head and including a normally submerged portion, a propeller shaft journalled in and projecting through a wall of the normally submerged portion of the housing structure, a propeller mounted on the outer end of the propeller shaft, driving connections extending through the housing structure from the power head to the propeller shaft and comprising a variable slippage fluid clutch mechanism, said fluid clutch mechanism comprising a shiftable valve element for regulating the torque transfer factor of the fluid clutch, a releasable positive-acting clutch for positively locking the variable slippage fluid clutch mechanism against slippage, a friction brake within the housing structure between the clutch and propeller shaft, said friction brake comprising a rotary friction element driven by the fluid clutch mechanism and a cooperating non-rotary friction element, and control mechanism for said valve element, positive-acting clutch and friction brake, said control mechanism comprising a common manually shiftable control element to which said mechanism is responsive to first release the positive-acting clutch and then coincidentally and progressively move the shiftable valve element toward a position of minimum torque transfer and to apply the friction brake.

15. In an outboard motor, a power head, housing structure depending from the power head and including a normally submerged portion, a propeller shaft journalled in and projecting through a wall of the normally submerged portion of the housing structure, a propeller

mounted on the outer end of the propeller shaft, driving connections extending through the housing structure from the power head to the propeller shaft and comprising a variable slippage fluid clutch mechanism, said fluid clutch mechanism comprising a shiftable valve element for regulating the torque transfer factor of the fluid clutch, a releasable positive-acting clutch for positively locking the variable slippage fluid clutch mechanism against slippage, a friction brake within the housing structure between the clutch and propeller shaft, said friction brake comprising a rotary friction element driven by the fluid clutch mechanism and a cooperating non-rotary friction element, and control mechanism for said valve element, positive-acting clutch and friction brake, said control mechanism comprising a common manually shiftable control element to which said mechanism is responsive to first release the positive-acting clutch and then progressively move the shiftable valve element toward a position of minimum torque transfer and to progressively apply the friction brake.

16. In an outboard motor, a power head, housing structure depending from the power head and including a normally submerged portion, a propeller shaft journalled in and projecting through a wall of the normally submerged portion of the housing structure, a propeller mounted on the outer end of the propeller shaft, driving connections extending through the housing structure from the power head to the propeller shaft, said driving connections comprising a variable slippage fluid clutch, shiftable valve means for controlling the slippage of the fluid clutch, a friction brake within the housing structure between the fluid clutch and propeller shaft, said friction brake comprising a rotary friction element driven by the fluid clutch and a cooperating non-rotary friction element, and operating mechanism for said valve means and said brake which includes a common manually shiftable control element to which said mechanism is responsive to successively shift the valve means to a position of maximum fluid clutch slippage and to apply the friction brake.

17. In an outboard motor, a power head, housing structure depending from the power head and including a normally submerged portion defining a cavity, a fluid clutch contained within said cavity, said cavity providing a fluid reservoir space adjacent the fluid clutch, said fluid clutch comprising relatively rotary members and a space therebetween that is in communication with the reservoir space adjacent the fluid clutch, power transmission means between one of the relatively rotary members of the fluid clutch and the power head, a propeller shaft journalled in a wall of the normally submerged portion of the housing structure with its inner end portion extending into the coupling fluid reservoir space of said cavity and coupled to the other of the relatively rotary members of the fluid clutch, a coupling fluid within the coupling fluid reservoir space of said cavity, a friction brake within said coupling fluid reservoir space between the fluid clutch and propeller shaft, said friction brake being submerged within the coupling liquid in the reservoir portion of said cavity and comprising a rotary friction element driven by the fluid clutch and a cooperating non-rotary friction element mechanism for applying and releasing the friction brake, heat generated in the fluid clutch and friction brake being rapidly dissipated to the

water in which the housing structure is submerged through said coupling fluid and housing structure.

18. The structure defined in claim 17 in further combination with a mechanical clutch releasably locking the relatively rotary members of the fluid clutch against relative rotation, said mechanical clutch also being submerged in the coupling liquid in the reservoir portion of the cavity.

19. In an outboard motor, a power head, housing structure depending from the power head and including a normally submerged portion defining a cavity, a fluid clutch contained within said cavity, said cavity providing a fluid reservoir space adjacent the fluid clutch, said fluid clutch comprising relatively rotary members and a space therebetween that is in communication with the reservoir space adjacent the fluid clutch, power transmission means between one of the relatively rotary members of the fluid clutch and the power head, a propeller shaft journalled in a wall of the normally submerged portion of the housing structure with its inner end portion extending into the coupling fluid reservoir space of said cavity and coupled to the other of the relatively rotary members of the fluid clutch, a coupling fluid within the coupling fluid reservoir space of said cavity, a mechanical clutch contained within the fluid reservoir space of said cavity for releasably locking the relatively rotary members of the fluid clutch against relative rotation, a releasable friction brake also located within the coupling fluid reservoir space of the cavity between the fluid clutch and propeller shaft, said mechanical clutch and friction brake being submerged within the coupling liquid in the reservoir portion of the cavity and comprising a rotary friction element driven by the fluid clutch and a cooperating non-rotary friction element, and mechanism for applying and releasing the mechanical clutch and applying and releasing the friction brake, said mechanism comprising a single manually-operated control element responsive to which said mechanism is responsive to successively release the mechanical clutch and set the friction brake, heat generated in the fluid clutch and friction brake being rapidly dissipated to the water in which the housing structure is submerged through said coupling liquid and housing structure.

20. In an outboard motor, a power head, housing structure depending from the power head and including a normally submerged portion defining a cavity, a fluid clutch contained within said cavity and comprising a casing-acting shell journalled for rotation within said cavity, and a rotor journalled within said casing-acting shell and coupled thereto by an interposed fluid-driving medium, a propeller shaft journalled in and projecting through the normally submerged wall portion of the housing structure and coupled to the rotor of the fluid clutch, mechanical driving connections extending through said housing structure to the shell-like casing of the fluid clutch and positively driving the latter, a releasable mechanical clutch interposed between the shell and rotor of the fluid clutch, a releasable friction brake interposed between the propeller shaft and housing structure, said mechanical clutch and friction brake also located within said cavity, and mechanism for operating the mechanical clutch and friction brake, the last-said mechanism comprising a single manually-operated control element responsive to a unidirectional movement of which the said mechanism will first

release the mechanical clutch and then progressively apply the friction brake.

21. In an outboard motor, a power head, housing structure depending from the power head and including a normally submerged portion defining a cavity, a variable slippage fluid clutch contained within the cavity and comprising relatively rotary inner and outer fluid coupled bodies, a propeller shaft journalled in and projecting through a wall of the normally submerged portion of the housing structure coupled to one of the relatively rotary bodies of the variable slippage fluid clutch, mechanical driving connections extending through the housing structure from the power head to the other relatively rotary body of the fluid clutch and positively driving the latter, valve means controlling the slippage of the fluid clutch and comprising a valve element mounted for shifting movements between positions of minimum and maximum fluid clutch slippage, a releasable mechanical clutch for positively locking the relatively rotary bodies of the fluid clutch against relative rotation and comprising relatively shiftable cooperating clutch elements each mounted for rotation with a different one of the relatively rotary bodies of the fluid clutch, a releasable friction brake interposed between the propeller shaft coupled body of the fluid clutch and the housing structure, said valve element, mechanical clutch and friction brake being also located in the said cavity of the normally submerged portion of the housing structure, and mechanism for operating the valve element, mechanical clutch and friction brake, the last said mechanism comprising a single manually operable control element responsive to unidirectional movement of which the said mechanism will successively release the mechanical clutch, shift the valve of said valve element to a position of maximum clutch slippage, and progressively set the friction brake.

22. In an outboard motor, a power head, housing structure depending from the power head and including a normally submerged portion, a propeller journalled in the submerged portion of the housing structure, a variable slippage fluid clutch mounted in said housing structure intermediate the power head and propeller shaft, said variable slippage fluid clutch comprising a journalled rotary shell defining a pump chamber, a rotor working within said pump chamber and journalled in said rotary shell for rotation with respect thereto, said motor having a circumferentially-spaced outwardly-opening generally radially disposed vane channel in its peripheral portion, and a vane slidably mounted in said vane channel and responsive to centrifugal action resulting from rotor rotation to make varying degrees of sealing engagement with the inner peripheral surface of the shell increasing with the speed of rotation of the rotor, a source of coupling fluid in communication with said pumping chamber, means positively driving the rotary shell of the fluid clutch from the power head, and means positively driving the propeller from the fluid clutch rotor.

23. In an outboard motor, a power head, housing structure depending from the power head and including a normally submerged portion, a propeller journalled in the submerged portion of the housing structure, a variable slippage fluid clutch mounted in said housing structure intermediate the power head and propeller shaft, said variable slippage fluid clutch comprising a jour-

nalled rotary shell defining a pump chamber, a rotor working within said pump chamber and journalled in said rotary shell for rotation with respect thereto, said rotor having circumferentially-spaced outwardly-opening generally radially disposed vane channels in its peripheral portion, and vanes slidably mounted in said vane channels and responsive to centrifugal action resulting from rotor rotation to make varying degrees of sealing engagement with the inner peripheral surface of the shell increasing with the speed of rotation of the rotor, a source of coupling fluid in communication with said pumping chamber, means positively driving the rotary shell of the fluid clutch from the power head, and means positively driving the propeller from the fluid clutch rotor.

24. The structure defined in claim 23 in further combination with a spring yieldingly biasing one of the rotor vanes outwardly in the direction of the cooperating inner peripheral surface of the shell, whereby to assure the establishment of a sufficient fluid seal between said vane and the shell in a static condition of the rotor, the other vanes being dependent solely upon centrifugal action to maintain sealing engagement with the inner peripheral surface of the shell.

25. In an outboard motor, a power head, housing structure depending from the power head and including a normally submerged portion defining a cavity, a variable slippage fluid clutch contained within said cavity, said fluid clutch

comprising a rotary shell journalled in the housing structure and defining a pump chamber, and a fluid coupled rotor working in the pump chamber and journalled to the rotary shell for independent rotation, a propeller shaft positively coupled to the pump rotor and extending therefrom through and journalled in a wall of the submerged portion of the housing structure, a propeller on the outer end of said propeller shaft, 10 a power head driven drive shaft extending downwardly through the housing structure into said cavity, a beveled gear fast on the lower end of said drive shaft, and an intermeshing beveled gear fast on the shell of the fluid clutch.

15 26. The structure defined in claim 25 in which said cavity provides a driving fluid reservoir space largely surrounding the fluid clutch and beveled gears, a coupling liquid in said reservoir space to a level above said fluid clutch and gears, and 20 passages providing communication between the pumping chamber of the fluid clutch and said fluid reservoir space.
